W. C. O'BRIEN

TAKE-UP FOR FLATIRON CONDUCTORS

Filed May 24, 1920

UNITED STATES PATENT OFFICE.

WILLIAM C. O'BRIEN, OF BALTIMORE, MARYLAND.

TAKE-UP FOR FLATIRON CONDUCTORS.

Application filed May 24, 1920. Serial No. 383,953.

To all whom it may concern:

Be it known that I, WILLIAM C. O'BRIEN, a citizen of the United States, residing at Baltimore, in the State of Maryland, have invented certain new and useful Improvements in Take-Ups for Flatiron Conductors, of which the following is a specification.

Electrically heated flat irons are usually each provided with a short length of flexible 10 conducting cord equipped with fittings at its ends, one for attachment to the iron and the other for attachment to the electric fixture connected to a current source. As the operator moves the iron forward on the ironing 15 board, the cord drags after the iron without interfering with the work; but upon the backward stroke of the iron the cord slackens and doubles up on the board behind the iron and hinders the work of the operator.

20 In order to overcome these difficulties, I have provided means whereby as the iron is used the slack in the electric cord is taken up at all times. This takeup device comprises a free-running spring reel mounted 25 upon a suitable base, which latter is provided with means for clamping it to a flexible conductor and also with guiding means for a cord, which latter is connected at one end to the reel and is provided at its other end 30 with means whereby it may be attached to the conductor at a point between the reel and the iron. With this arrangement, the slack in the conductor is constantly taken up and held off of the ironing board.

35 In the accompanying drawing which illustrates my invention,

Fig. 1 is a view showing a flat iron connected to an electric fixture, with the take-up device applied to the connecting conductor, the operation of the device being 40 illustrated by dotted lines;

Fig. 2 is a bottom plan view of the take-up device;

Fig. 3 is a side elevation of the same, 45 partly in section;

Fig. 4 is a central section through the reel, showing also the plate which supports the reel spindle and cord guide; and,

Fig. 5 is a top plan view of the take-up 50 device.

Referring to Fig. 1 of the drawing, A indicates a flat iron, B indicates an electric fixture, such as a lamp socket, connected to a suitable current source, and C indicates a

55 flexible electric conductor such as is usually supplied for flat irons, having suitable plugs

or attachments at its ends for connecting with the flat iron and the fixture. The take-up device of my invention is shown at D in Fig. 1, mounted upon the conductor C, and 60 1 indicates the cord extending from said device and connected to the conductor.

The take-up device, as shown in Figs. 2 to 5, inclusive, of the drawing, comprises a base 2, which is preferably made of a circular 65 piece of wood or other light material, and secured to one side of this base by screws 3 and 4 is a sheet metal plate 5, having a part 5^a which projects laterally from the base and extends at right angles thereto. 70 Upon this part 5^a is mounted a flaring cord guide 6, hereinafter referred to. A spindle 7 is secured to the plate 5 and projects outwardly from the central portion of the base, and upon this spindle is mounted a 75 reel 8, the latter being made of wood or other light material and adapted to turn freely on the spindle. The reel has in one side a circular depression 8^a, in which is arranged a flat spiral spring 9, the latter 80 having one end attached to the reel by a screw 10 and having its other end fitting within a slot 7^a in the spindle. A cup-shaped cover 11 fits on to the base and encloses the reel, and this cover is held in 85 place by a nut 12, on the outer end of the spindle 7. The cord 1 has one end attached to the reel, and its opposite end extends through an opening in the side of the cover and thence through the funnel-shaped cord 90 guide 6, which latter guides the cord in a line tangential to the reel and substantially parallel with a groove g, which is cut in the back of the base and extends diametrically across the latter. A clamping plate 95 13 is pivotally mounted upon the screw 4, at the back of the base, and is provided with a notch 13^a for engaging the screw 3, as shown in Figs. 2 and 3. Thumb nuts 14 are provided upon the screws 3 and 4 for 100 pressing the clamping plate against the electric conductor C. The cord 1 is provided at one end with suitable means for securing it to the electric conductor, such as the tape 1^a.

In the practical use of the invention, the take-up device is secured to an electric conductor, as shown in Fig. 1, by arranging the conductor in the groove g and tightening the clamping plate 13 against the conductor. The cord 1 is then drawn out against the action of the spring, and it is tied to the 105 110

conductor at a point between the reel and the flat iron and sufficiently spaced from the reel to cause all of the slack in the conductor to be taken up and formed into 5 a loop *c*, as shown in dotted lines in Fig. 1, when the iron is at its nearest point to the fixture *B*. It will be evident that as the iron is moved from the dotted line position, in Fig. 1, to the full line position, 10 the cord will be pulled out of the reel and the loop in the conductor will straighten, and as the iron is moved backward the tension of the spring in the reel will cause the slack in the conductor to be taken up in the 15 form of a loop which is out of contact with the ironing board and out of the way of the operator. If the iron is moved further back than the dotted line position shown in Fig. 1, of course, the loop will also straighten 20 out. In order that the device may work smoothly, the groove in which the flexible conductor fits is arranged centrally of the base, and the guide for the cord is arranged

so that the cord will be directed parallel with said groove and with the conductor and 25 will not pass around any corners in taking up and slackening off the conductor.

It will be obvious that the invention is 30 equally applicable to gas heated irons, where- in the gas for heating the irons is conducted 35 from a gas outlet or fixture to the iron through a flexible tube or conductor.

What I claim is:

A take-up device for flexible conductors comprising a circular base having a dia- 35 metrical groove on one side and a spindle projecting centrally from its opposite side, means on the base for clamping the conductor in said groove, a free-running spring reel on said spindle, a cord on the reel, a 40 cord guide secured to the base and adapted to guide the cord in a line tangential to the reel and substantially parallel with said groove, and a casing enclosing the reel.

In testimony whereof I affix my signature.

WILLIAM C. O'BRIEN.
